UNITED STATES PATENT OFFICE.

NEWMAN R. MARSHMAN, OF NEW YORK, N. Y.

MECHANICAL MUSICAL INSTRUMENT.

SPECIFICATION forming part of Letters Patent No. 277,309, dated May 8, 1883.

Application filed April 12, 1882. (No model.)

To all whom it may concern:

Be it known that I, NEWMAN R. MARSHMAN, of New York, in the county and State of New York, have invented a certain new and 5 useful Improvement in Mechanical Musical Instruments, of which the following is a specification.

My improvement consists in the combination, in a mechanical musical instrument, with 10 a rest for a traveling music-sheet having ducts which communicate with sound-producing devices, of a removable wind-chest arranged above the rest, and a device for connecting said wind-chest with the means whereby wind is induced 15 to the sound-producing devices for operating them. The device for connecting the wind-chest with the means for inducing wind to the wind-chest may consist of a flexible pipe leading from bellows or from the mouth of the performer. Preferably the wind-chest will have 20 combined with it a spring or springs for impelling it toward the rest, or it will be weighted to subserve the same end.

In the accompanying drawings, Figure 1 is 25 a sectional side view of a mechanical musical instrument embodying my improvement, and Fig. 2 is a plan of the same.

Similar letters of reference designate corresponding parts in both figures.

30 A designates the body of the musical instrument. It may be of any suitable materials and construction, and, as shown, is provided with force-bellows B and a receiver or equalizer, C.

35 D designates a rest, over which a perforated music-sheet, E, is caused to travel by means of feed-rollers F, one of which is provided with a hand-crank, whereby it may be conveniently driven or actuated. Links or other connections between cranks on the driving feed-roller serve to impart motion to the bellows. Reeds are arranged in cells which communicate with ducts or apertures in the rest D, that are controlled by the music-sheet E.

40 G designates a removable wind-chest arranged above the rest D. It works up and

down in guideways in rails H, projecting above the body A of the instrument and forming guides for the music-sheet. Springs I impel it downward toward the rest, and may be 50 moved or swung aside to permit of its removal to gain access to the rest. A flexible pipe, J, of india-rubber or other suitable material, connects the receiver or equalizer C with the wind-chest G, and to enable the latter to be entirely 55 removed from the remainder of the instrument this pipe is attached to a nipple on the wind-chest, communicating with its interior in such manner that it may be slipped off the nipple. Any other connection between the receiver or 60 equalizer and wind-chest that will permit of its removal may be employed.

If desirable, the bellows and receiver or equalizer may be omitted, and the flexible pipe J may be provided with a mouth-piece, where 65 by the operator is enabled to conveniently supply the necessary wind from his lungs.

What I claim as my invention, and desire to secure by Letters Patent, is—

1. In a mechanical musical instrument, the 70 combination, with a rest for a traveling music-sheet having ducts which communicate with sound-producing devices, of a removable wind-chest and a device for connecting said wind-chest with the means whereby wind is 75 induced to the sound-producing devices for operating them, substantially as specified.

2. In a mechanical musical instrument, the combination, with a rest for a traveling music-sheet having ducts which communicate 80 with sound-producing devices, of a removable wind-chest, a spring or springs, or the equivalent thereof, for impelling it toward the rest, and a device for connecting said wind-chest with the means whereby wind is induced to the 85 sound-producing devices for operating them, substantially as specified.

NEWMAN R. MARSHMAN.
